UNITED STATES PATENT OFFICE.

GEORGE DICKIE, OF SAN FRANCISCO, CALIFORNIA.

TRANSOM-OPERATING DEVICE.

No. 921,596.

Specification of Letters Patent.

Patented May 11, 1909.

Original application filed September 1, 1908, Serial No. 451,140. Divided and this application filed March 2, 1909.
Serial No. 480,945.

To all whom it may concern:

Be it known that I, GEORGE DICKIE, a citizen of the United States, residing in the city and county of San Francisco and State of California, have invented new and useful Improvements in Transom-Operating Devices, of which the following is a specification.

My invention relates to a device which is especially designed for the opening, closing and automatically locking of transoms and like closures, such as are employed above doors or windows.

It consists in the combination of parts, and in details of construction which will be more fully explained by reference to the accompanying drawing, in which—the figure is a vertical section showing the device.

It is the object of my invention to provide a means for readily opening and closing hinged or pivoted transoms, which are usually located above doors or windows, and which are to be opened to a greater or less extent to provide ventilation.

My invention is designed to provide a device in which the operating mechanism is compact, and substantially concealed within the door or window casings, in such a manner as to avoid the projection of these parts into view.

A represents a transom which is hinged or pivoted as at A' so that the upper edge is movable in an arc of a circle about this hinge. It will be understood that this transom may also be hinged at the top, or centrally, so that one portion will turn outward, and the other inward; the operating devices being essentially the same in each case.

2 is a rod or bar fixed to the transom a short distance from the pivot or hinge line thereof, and extending horizontally to a point where it is connected with the operating device. A connection is made by means of links 3, and these links are connected with a screw-threaded nut 4, which is fitted to travel within a hollow cylindrical and internally threaded sleeve 6. This sleeve is journaled in plates 7 which are let into the window casing, and thus this portion of the apparatus is effectively concealed. The sleeve has fixed upon it, near the outer end, a sprocket-wheel 8. This sprocket-wheel is preferably fixed at a point contiguous to the casing, and within a channel made in the cas-

ing, which channel may be covered or inclosed in any suitable manner.

An endless chain 9 passes around the sprocket-wheel, and extends downward within the channel in the casing, the lower end being exposed to a sufficient length to allow the operator to pull the chain, and thus turn the sprocket in one direction or the other. The turning of the sprocket also turns the interiorly screw-threaded cylinder 6, and the nut 4 will thus be caused to travel in one direction or the other. This nut has preferably a flattened extension 5, which is threaded at its upper and lower edges continuously with the thread upon the nut. This extension is of such length as to serve as a guide to prevent the nut binding within the threads of the sleeve. The outer end of the extension 5 is connected by a link 3 with the end of the arm 2, which is fixed to the transom as shown. The link may also be made jointed, if found desirable, so that it can bend at this joint, and thus allow the outer end to follow the arc of curvature of the arm 2, caused by the opening or closing of the transom, without allowing the link to bind in the interior of the outer end of the screw-threaded drum. The operation will then be as follows: By pulling upon one side or the other of the endless chain 9, the sprocket wheel 8 and the drum 6, to which it is fixed, will be revolved, the drum turning in its journal-bearings, and this causes the nut 4 to advance within the drum, and through its connection with the transom bar 2, the transom will be moved so as to open or close.

The device is compact and cheap, and being almost entirely inclosed and out of view is well adapted for high class buildings and residences.

It will be seen that by reason of the nut, the screw-threads of the nut and the inclosing drum, the device will act automatically as a lock to retain the transom at any point to which it may have been opened, and no access can be had from the transom to the chain by which the mechanism is actuated.

The present application is a division of a former application, filed by me on the 1st day of September, 1908, Serial Number 451,140, for certain other improvements in transom-operating devices.

Having thus described my invention, what I claim and desire to secure by Letters Patent is—

1. In a device for opening and closing transoms and the like, a horizontally journaled interiorly threaded drum, a sprocket fixed to the drum, an endless chain passing around the sprocket, extending downward to a point within reach of the operator, a screw-threaded nut fitting the interior of the drum, and a link connecting the nut with the transom.
- 10 2. In a device for opening and closing transoms and the like, a horizontally journaled, interiorly screw-threaded drum fixed within the casing, a screw-threaded nut fitting the threads of the drum, said nut having an extended screw-threaded guide plate, a flexible link having one end connecting with the outer end of said plate, a bar fixed to said transom at a distance from the pivot of said transom, and intersecting the axis of said screw, with which bar the opposite end of the link is connected, a sprocket fixed to the exterior of the screw-threaded drum, and an endless chain passing around said sprocket and extending downwardly within reach of an operator.
- 20 3. In a transom opening, closing and lock-

ing device, connected plates, a casing having a recessed space, the outer of said plates fixed to the casing, and an inclosed groove or channel extending downwardly in the outer portion of the casing, a horizontal, interiorly screw-threaded drum journaled and turnable between the plates, a nut having a flat-threaded extension, said nut fitting and turnable in the threads of the drum, a sprocket fixed upon the drum in line with the casing channel, an endless chain passing around said sprocket extending downwardly within the channel, a hinged or pivoted transom, a bar fixed thereto at a distance from the pivot, and extending to a point in vertical plane with the guide plate of the nut, and flexible links connecting said plate with the transom-actuating bar.

In testimony whereof I have hereunto set my hand in presence of two subscribing witnesses.

GEORGE DICKIE.

Witnesses:

HENRY P. TRICOU,
CHARLES A. PENFIELD.
